AIR CONTROL MECHANISM AND SWITCH FOR OIL BURNERS

Filed Aug. 21, 1943

UNITED STATES PATENT OFFICE

2,446,834

AIR CONTROL MECHANISM AND SWITCH
FOR OIL BURNERS

Daniel Kaufman, New Haven, Conn., assignor, by
mesne assignments, to The Oil Equipment
Manufacturing Corporation, New Haven, Conn.,
a corporation of Connecticut

Application August 21, 1943, Serial No. 499,586

2 Claims. (Cl. 206—53)

1

This invention relates to new and useful improvements in air control mechanism, particularly as applied to gun type oil burners.

A principal object of the invention is to provide a mechanism of this character wherein the heat in the combustion chamber will be conserved, the volume of air admitted to the combustion chamber easily and effectively controlled, and the parts arranged so that the oil burner will not function until the air ports are opened. This latter sequence of operations eliminates the hazard of an explosion with its destructive results. A further object is to provide a device that will be relatively simple in its operation, constructed at the minimum cost and adapted to be assembled either before or after the oil burner mechanism is installed. Other and further objects of the invention will become apparent from the following description of a preferred form of the invention in connection with the accompanying drawings, wherein like numerals of reference indicate like parts in the several figures.

In the drawings:

Figure 1 illustrates this improved air control mechanism, the parts in section being taken generally upon line 1—1 of Figure 2;

Figure 2 is another view thereof;

Figure 3 is a fragmentary view, the parts in section being taken generally upon line 3—3 of Figure 2;

Figure 4 is an enlarged cross sectional view of the fluid cylinder and associated parts, the parts in section being taken generally upon line 4—4 of Figure 2;

Figure 5 is a diagrammatic view of the electric wiring; and

Figure 6 is an enlarged view of the piston head and flap valve.

Referring to the drawings, the numeral 5 indicates a fan housing of a gun type oil burner, through one end of which is an opening 48; 6 is a portion of an electric motor mounted therein; and 7 a fan fixed on the motor armature. Adjacent to the fan housing 5 is a combustion chamber (not shown), into which air is driven by the fan 7 from the fan housing 5. Alongside the fan housing 5 is a valve housing 8, shown herein as being substantially rectangular in form, with a bottom portion 9, through which is an opening or port 11 and surrounding wall portions 10. Fixed to the valve housing 8 at one end is an electric magnet 12 and to the opposite end a fluid cylinder 13. This latter is closed at one end and provided with a head 14 at the other end, through which passes a piston rod 15, having a piston 16 thereon within the cylinder 13. Through the piston is a port 17 and on one side

2

thereof is a flap valve 18, which operates in a conventional manner. Through this flap valve, and in register with the ports 17 are the ports 43 of less area than the ports 17. The cylinder 13 is filled with a fluid, preferably oil, and as the piston 16 moves toward the magnet, the oil from the upper end of the cylinder flows through the ports 17 and by the flap valve 18, which opens outwardly, and into the lower end of the cylinder. When the piston moves in the reverse direction the fluid passes through the ports 43 and ports 17 to the upper end of the cylinder. As the area of the ports 43 is less than the ports 17, the piston will move toward the magnet at an accelerated speed relative to its movement in the opposite direction.

Within the valve housing 8, and slidably alongside the bottom thereof under the caps 41, is a plate 19 having one or more rectangular ports 20 therethrough, a lip 21 at its lower end, and an offset lug 22 at its upper end. Projecting through an end wall 10 of the valve housing and the offset lug 22 is an adjusting screw 23 having a nut 24 thereon. Endwise movement of this screw is prevented by a collar 25 fixed thereon. By manipulation of the screw 23 the plate 19 is moved toward and away from the magnet 12, thereby adjusting its relative position within the valve housing 8. Movable on this plate 19, and held in engagement therewith by the lugs 26, is a slide 27, having one or more rectangular ports 28 therethrough, corresponding in number with the ports 20 and of substantially the same size and shape. In one position of the slide relative to the plate 19, the ports 20 and 28 are in register with each other and fully open. On the slide 27 is an armature block 29, positioned opposite the magnet 30 of the electric magnet 12. The piston rod 15 projects through a lug 31 on the slide 27 and is adjustably secured thereto by the nuts 32. Connected with a fixed part is a contact plate 33, and adjacent thereto a movable contact plate 34, which projects into the path of a contact arm 35 on the slide 27.

In the diagrammatic view, 36 indicates a thermostat, placed in any convenient position and suitably wired, the arm 37 of which in one of its positions engages a contact point 38, and thereby closes an electric circuit. The thermostat is connected to the magnet by a wire, the contact point 38 with a house or other convenient circuit by a wire 44, and with the fixed contact plate 33 by the wire 40. The contact plate 34 is connected with one brush 41 of the motor 6 by the wire 45 and the other brush by a wire 42 to the house circuit.

As shown in the drawings, the air inlet ports through the slide 27 and the plate 19 are closed

and no air can pass therethrough into the housing 5. This prevents cold outside air from passing into the combustion chamber, cooling the walls thereof as well as the furnace or boiler flues and cooling the entire heating plant. The system begins to function when the arm 37 of the thermostat at a predetermined temperature engages the contact point 38 and closes the electric circuit. The current then energizes the magnet 12. Before being energized, the armature 30 of the magnet 12 is in substantially the position shown in the drawings, that is, in engagement with the armature block 29 on the slide 27. When the magnet is energized the armature 30 is drawn into the body thereof and pulls with it the slide 27. During this action the piston 16, through the piston rod 15, is moved upwardly in the cylinder 13, the fluid therein passing through the port 17 from above to below the piston. This movement of the slide 27 uncovers the air inlet ports 20 through the plate 19 and when near the upward limit of its movement the contact arm 35 upon the slide 27 engages the contact plate 34 and forces it against the fixed contact plate 33, closing the circuit to the motor 6. Rotation of the motor starts both the fan 7 and the oil pump (not shown), which then function in a well known and conventional manner.

The fan draws air into the housing 5 through the ports 28 and 20 and forces it into the combustion chamber where the oil supplied by the pump is atomized and unites with the air, providing a proper mixture for combustion purposes. If and when the temperature is raised, action of the thermostat as a result thereof moves the arm 37 away from the contact point 38 upon the electric circuit. Engagement of the contact arm 35 with the contact plate 34 is thus broken and the current to the motor 6 is shut off, thus stopping the oil pump and shutting off the oil supply and also rotation of the fan 7.

The drop speed of the slide 27 is determined by the speed of travel of the fluid in the cylinder 13 under the piston to the top thereof through the ports 43 and 17. As the port 43 is smaller in area than the port 17 the speed of the down movement of the slide 27 is much slower than its up speed. When the temperature returns to the predetermined degree the sequence of operations hereinbefore described are repeated.

Due to the fact that the slide 27 moves downwardly at a relatively slow speed the air ports close slowly, thus permitting sufficient air to pass through the ports 28 and 20 to drive out any products of combustion that may remain in the combustion chamber. The combustion chamber is thus clear of gases, atomized fuel and products of combustion, resulting from the last prior operation of the burner. The volume of air admitted to the combustion chamber decreases as the slide 27 moves downwardly until the ports are entirely closed, at which time the clearing operation of the air within the combustion chamber has completed its work and no more air is admitted.

Heretofore in the conventional type of mechanism of this character, some gases, atomized fuel and products of combustion have remained within the combustion chamber after the burner has ceased to function, with the result, that upon occasion, at the next starting of the burner, there is a premature explosion with disastrous results to both the burner and adjacent mechanism. When the rectangular ports are fully closed, the lower edge of the slide 27 rests upon the lip 21 on the plate 19, thus limiting its downward move-

ment. The required volume of air passing through the ports to provide a proper mixture of vaporized oil and air may be varied. This is accomplished by adjusting the position of the plate 19 toward and away from the magnet 12 through manipulation of the screw 23 therewith. As the plate 27 rests upon the lip 21 the armature 30 is pushed into the magnet body 12 as the plate 19 moves toward the magnet. There is thus less travel for the slide 27 before the arm 35 engages the contact plate 34.

The ports 20 and 28 are shown herein as rectangular, but they may be of other shapes if desired.

15 Some parts of this mechanism are insulated from other parts. In such instances, any approved form of insulation may be used.

16 Minor changes and alterations, within the spirit and scope of the appended claims, may be 20 made in the preferred embodiment of the invention illustrated herein.

What is claimed is:

1. In a mechanism of this character described, air control means comprising a housing member 25 having an inlet port therethrough, a plate having ports therethrough and adjustable relatively to the inlet port of the housing, a vertically movable slide having ports therethrough movably mounted on the plate to cause the ports to cover and uncover the ports through said plate on movement of the slide relatively to the plate, means to stop the downward movement of the slide, said slide being biased by gravity into engagement with said stop means, an electromagnet to move the slide 35 upwardly, the upward movement of said magnet being limited to an amount sufficient to effect uncovering of the plate ports by the slide ports when the plate is in its lowermost adjusted position, means for energizing said magnet, and retarding mechanism for limiting the speed of movement of the slide downward by gravity away from said magnet, the adjustment of said plate varying the area of the ports uncovered by the slide in its upper position.
- 40 2. A mechanism as in claim 1, including an electric switch mounted on the housing adjacent the slide, and means upon said slide to engage and actuate said switch.

DANIEL KAUFMAN.
